ELECTRICAL CONTACT BRUSH

Ernest S. McLarn, Manhasset, N. Y., assignor to
 International Standard Electric Corporation,
 New York, N. Y., a corporation of Delaware

Application July 29, 1944, Serial No. 547,172

1 Claim. (CL 200—166)

1

My invention relates to electrical contact brushes and more particularly, although not exclusively, to brushes for selector switches for telecommunication systems.

An object of the invention is the provision of a contact brush which when used in a telephone circuit does not give rise to microphonic noises and clicks. These noises are due largely to the movement of adjacent switches and the operation and release of associated clutch magnets. Building vibrations are also the cause of clicks.

According to one feature of my invention, a contact brush comprises a pair of parallel spring members fixed to a supporting means at one end and separated at the other end by a small block of resilient material. This block is located in the region where one of said spring members is provided with a contact surface for wiping over the contact terminals or pins. The separating block of resilient material has the effect of damping vibration of the spring members as they stand on contact pins on terminals and effectively preventing microphonic noises in the telephone circuit.

The above and other features will be fully understood from a reading of the following detailed description of one embodiment of my invention taken in conjunction with the accompanying drawings, in which:

Fig. 1 is a side elevation of a brush unit;

Fig. 2 is a section taken on the line 2—2 of Fig. 1;

Fig. 3 is a section taken on the line 3—3 of Fig. 2 showing at A and B respectively the positions of the brush springs when making contact with a terminal pin and when between adjacent terminal pins.

Fig. 4 is a side elevation of the brush guide;

Fig. 5 is an end elevation of the brush guide; and

Fig. 6 is a section taken on the line 6—6 of Fig. 4.

My invention is described as applied to a flat-type selector switch of the kind disclosed in Patent No. 2,330,812 issued October 5, 1943, to Gerald Deakin. Only one brush unit is illustrated in the accompanying drawings but it will be understood that in practice eight or any other suitable number will be mounted to the same brush carriage which is moved back and forth in a reciprocatory manner over the flat terminal bank.

Referring to Figs. 1 and 2, the brush unit is supported on a molded brush carriage 1 by two pins 2 which are secured in the carriage by

2

spring clips 3 which engage in grooves in the ends of the pins 2.

The brush unit comprises a punched fiber strip 4 provided with holes for the passage of the pins 2 and to which are secured by rivets or eyelets 5 two outer phosphor bronze brush springs 6 and two inner brush springs 7. A pair of depending supports 8 for a brush guide 9 is secured at each end of the strip 4 by an eyelet 10. The upper portions of the outer brush springs 6 are formed with lateral extensions 11 which are shaped to wipe over each side of a feeder bar 12.

The lower ends of the inner brush springs 7 are formed with lateral contact surfaces adapted to wipe over the contact pins 13 in the bank, which pins are made of a hard metal such as phosphor bronze or stainless steel. The inner and outer brush springs 6 and 7 are in contact for the major portion of their length but near the tip the inner brush spring 7 is bent at an angle to form a space between the tips as shown in Fig. 2. At this region the sides of the spring 7 are also bent back as illustrated in Fig. 3. A small block 14 of vibration-damping resilient material, such as Neoprene, is positioned in the space between the tips of each pair of brush springs 6, 7 and is held in position by a lip 15 on the lower edge of the spring 6 and by the bent back sides of the spring 7. Oscillograph tests have shown that the block of soft material 14 effectively damps vibration of the brushes, prevents vibration of the springs and reduces microphonic contact between the brushes and the terminal pins 13.

Figs. 4, 5 and 6 show the construction of the brush guide 9 which comprises a molded Bakelite block formed with two slots 16 to accommodate inturned ends of the supports 8. At the center the block is slotted on both sides where the brushes pass over it to provide a section 17 of reduced thickness which limits the movement of the brushes when they are between terminal pins and so prevents short circuits between the pins. The lower portion of the section 17 of reduced thickness is cut away as at 18. A slot 19, in which the pins 13 project and slide, extends the full length of the guide and is outwardly flared at its lower edges as shown in Fig. 6. The ends of the slot 19 are also flared as shown in Fig. 5 in order to guide the pins into the slot. The guide assures alignment of the brushes with the pins 13 and the accurate making and breaking of the contact. It prevents one brush from projecting further between adjacent pins than the

other and thus allows of maximum rubbing contact by each brush which in practice is about 85% of the distance between pin centers.

It will be understood that while I have chosen to illustrate my invention as applied to a flat-type selector switch, it is applicable to many other types of switch without departing from the scope of the invention as defined by the appended claim.

I claim:

A contact brush for use in apparatus wherein contact and alignment are effected in succession between the contact brush and a plurality of linearly mounted contact pins, said contact brush comprising a first pair of substantially parallel metallic spring members having inner contact surfaces at one end of each for making electrical contact with said contact pins, supporting means for said spring members, a second pair of substantially parallel spring members mounted on said supporting means one behind each of the first pair of spring members and vibra-

tion-damping blocks of homogeneous structure mounted one between and supported solely by each two adjacent spring members of said first and second pairs of spring members.
